Primary Examiner — Raphael Barkai*Assistant Examiner* — Randall Gholson(74) *Attorney, Agent, or Firm* — Knobbe Martens Olson & Bear LLP**CLAIM**

I claim the ornamental design for a case, as shown and described.

DESCRIPTION

FIG. 1 is a top end view of a case showing my new design; FIG. 2 is a bottom end view of the embodiment of FIG. 1; FIG. 3 is a left side view of the embodiment of FIG. 1; FIG. 4 is a right side view of the embodiment of FIG. 1; FIG. 5 is a front view of the embodiment of FIG. 1; FIG. 6 is a back view of the embodiment of FIG. 1; FIG. 7 is a back perspective view of the embodiment of FIG. 1; and, FIG. 8 is a front perspective separated view of FIG. 1. The broken lines in FIGS. 1–8 are for illustrative purposes only and form no part of the claimed design.
